UNITED STATES PATENT OFFICE.

WILLIAM HEWITT, OF TRENTON, NEW JERSEY, ASSIGNOR TO THE TRENTON IRON COMPANY, OF SAME PLACE.

METALLIC FABRIC.

SPECIFICATION forming part of Letters Patent No. 314,576, dated March 31, 1885.

Application filed October 20, 1884. (No mod. 1.)

To all whom it may concern:

Be it known that I, WILLIAM HEWITT, a citizen of the United States, residing in Trenton, New Jersey, have invented an Improvement in Metallic Fabrics, which can be used either for fencing, for the making of screens or bed-bottoms, or for such other purposes as metallic or wire fabrics are ordinarily applicable to, of which the following is a specification.

The object of my invention is the construction of a cheap, durable, mechanically simple, and easily-manufactured metallic fabric.

To the above ends my invention consists in the combination, to form a metallic fabric, of a series of spirally-twisted metallic strips, rods, or pieces with a series of twisted wire cables connected in predetermined relationship to the twisted strips by having their strands embrace said strips, substantially in the manner shown and described.

In the accompanying drawings, Figure 1 is a plan view of a section of a fabric embodying my invention, and adapted for use as, for instance, a bed-bottom. Figs. 2, 3, and 4 are transverse sectional magnified views representing three forms of twisted strips, which are equally well adapted for use in the formation of my fabric.

Similar letters of reference indicate corresponding parts.

In the drawings, the spirally-twisted strips, rods, or pieces are designated by the letter A, while the cables which unite them to form the fabric are lettered B. The spirally-twisted strips are preferably formed from a strip of sheet metal or other malleable metal product produced by rolling, which is sectionally of greater breadth than thickness. Thus, for instance, in Figs. 1 and 2 these strips are represented as twisted from flat strips of metal of rectangular cross-section, while in Fig. 3 a strip is shown the section of which is elliptical. Again, in Fig. 4 a strip is represented down the center of which has been rolled a double bead, a, and the edges of which are slightly rounded. The form of the metal product or blank from which the twisted strip is made is therefore not essential, the only pre- requisite condition being that it should be of

such sectional outline as to permit of its being twisted to form a well-defined spiral in the resulting completed strip.

The office of the spiral twists of the strips is to retain from displacement the strands or wires composing the cables, which latter, in being twisted about the strips, lodge, so to speak, or seat themselves, about given spiral twists of said strips, and are thereby held in position.

The fabric is conveniently produced by first forming the spirally-twisted strips, and by then twisting the wires or strands which form the cables in such manner that in the act of the formation of the cables the said strands spread around or embrace the spiral strips, lodging, as already explained, in the turns or twists of said strips and embracing them.

My device is applicable for use as a fence by making certain of the spiral strips of greater length than others, as indicated in dotted lines by a^x in Fig. 1, so that the prolonged ends may be embedded in the ground, and the strips of which they are a part be thereby made to act as posts for the fence, the adjacent spiral strips in such employment becoming the pickets of the fence. It is also possible to employ wooden posts and apply the fabric to them, and, if desired, between the posts one or more prolonged strips may be provided.

In the drawings I have represented cables composed of two strands only. More than two stands may, if desired, be employed, although I prefer to use but two.

It is essential that the spiral twists of the strips should be sufficiently well defined to form seats about which the strands of the cables may firmly seat themselves, so that the cables cannot be displaced with respect to their position longitudinally upon the strips; and this is an important feature of the invention, for, were the conditions otherwise, it is apparent that it would be possible to withdraw or pull out any particular twisted strip, and thereby destroy the fabric.

It is of course apparent that while the cables cannot move longitudinally with respect to the twisted strips, they cannot also move in the direction of their own length, and this for the reason that any such movement is pre-

vented by the fact that their strands embrace the twisted strips.

Having thus described my invention, I claim and desire to secure by Letters Patent—

5 As a new article of manufacture, a metallic fabric composed of a series of spirally-twisted strips, rods, or pieces of metal and of a series of wire cables the strands of which embrace the strips, substantially as shown and described.

In testimony whereof I have hereunto signed to my name this 15th day of October, A. D. 1884.

WM. HEWITT.

In presence of—

F. C. LOWTHROP, Jr.,
J. BONSALL TAYLOR.
